(57) **CLAIM**

The ornamental design for an artificial worm plastic bait, as shown and described.

DESCRIPTION

FIG. 1 is a perspective view of an artificial worm plastic bait showing my new design;

FIG. 2 is a right side elevational view thereof;

FIG. 3 is a top plan view thereof;

FIG. 4 is a bottom plan view thereof;

FIG. 5 is a front elevational view thereof; and,

FIG. 6 is a rear elevational view thereof.

The broken lines in the drawing represent environmental subject matter that forms no part of the claimed design.
